(57) **CLAIM**

I claim the ornamental design for a portable medical equipment for clinical analysis, as shown and described.

DESCRIPTION

FIG. 1 is a perspective view of a portable medical equipment for clinical analysis showing the new design;

FIG. 2 is a front side view thereof;

FIG. 3 is a rear side view thereof;

FIG. 4 is a right side view thereof;

FIG. 5 is a left side view thereof;

FIG. 6 is a top view thereof; and,

FIG. 7 is a bottom view thereof.

The broken lines are included for the purpose of illustrating portions of the portable medical equipment for clinical analysis that form no part of the claimed design.
